HANGER FOR LUGGAGE OR THE LIKE

Samuel J. Holtzman, 8201 Symphony Drive,
Baltimore, Md. 21208

Filed Mar. 31, 1967, Ser. No. 6,465

Term of patent 14 years

(Cl. D80—8)

FIG. 1 is an elevational view taken from one side of a hanger for luggage or the like embodying my new design;

FIG. 2 is a top plan view thereof;

FIG. 3 is an elevational view taken from the side opposite that shown in FIG. 1;

FIG. 4 is a bottom plan view thereof; and

FIG. 5 is a cross-sectional view, on an enlarged scale, taken in the plane of line 5-5 of FIG. 3.

I claim:

The ornamental design for a hanger for luggage or the like, as shown.
